Paterson(57) **CLAIM**

The ornamental design for a boat as shown and described.

DESCRIPTION

The patent or application file contains at least one drawing executed in color. Copies of this patent or patent application publication with color drawing(s) will be provided by the Office upon request and payment of the necessary fee.

1. Boat

1.1 : Front, right perspective

1.2 : Front

1.3 : Rear

1.4 : Right

1.5 : Left

1.6 : Top

1.7 : Rear, left perspective

1.8 : Front, left perspective

1.9 : Rear, right perspective

The broken lines at the bottom of the boat illustrate a boundary of the design which forms no part of the claimed design. The remaining broken lines depict boundaries around the de-emphasized elements, which illustrate portions of the boat which form no part of the claimed design.
